L. J. WAHL

CLIPPER

Filed June 23, 1923

Teori Wahl

Leo J. Wahl.

W. Beck

Atty.

UNITED STATES PATENT OFFICE.

LEO J. WAHL, OF STERLING, ILLINOIS.

CLIPPER.

Application filed June 23, 1923. Serial No. 647,249.

To all whom it may concern:

Be it known that I, LEO J. WAHL, a citizen of the United States, and a resident of Sterling, in the county of Lee and State of Illinois, have invented certain new and useful Improvements in Clippers, of which the following is a full, clear, and exact description, reference being had to the accompanying drawing, forming part of this specification.

10

My invention relates primarily to clippers such as are used by barbers for cutting hair, though it is capable of advantageous use for other purposes as will be apparent to those skilled in the art to which it appertains.

One object of my invention is the provision of a device to be operated by an alternating electric current without the use of a circuit breaker or interrupter.

20 Another object of my invention is to arrange the electro-magnetic coils longitudinally of the handle to the end that they may be made of sufficient capacity to eliminate heating in operation.

25 Another object of my invention is to operate the moveable clipper blade by means of an armature moving toward and from the axes of the electro-magnetic coils.

Other objects of my invention will appear 30 and be described in the specification.

The novelty of my invention will be hereinafter more fully set forth and specifically pointed out in the claims.

In the accompanying drawing:

35 Fig. 1, is a plan view of a clipper embodying my invention in one form of construction.

Fig. 2, is a sectional side view of Fig. 1.

Fig. 3, is a plan view of the operating portions of a different form of construction.

40 Fig. 4, is an end view of Fig. 3.

Fig. 5, is a plan view of another form of construction.

Fig. 6, is a plan view of a still further 45 change in construction.

Fig. 7, is a sectional side view of Fig. 6.

The same numerals of reference are used to indicate identical parts in the various figures.

50 Referring to Figs. 1 and 2, the clipper comprises a handle 1, to the widened front end of which the stationary clipper blade 2 is attached and upon the upper face of the latter, the moveable clipper blade 3 is mounted, both of these clipper blades are preferably serrated as shown. A pair of

electro-magnetic coils 4 are mounted in the handle 1, with their axes longitudinally arranged therein, these coils being mounted upon a laminated or other suitable horse-shoe-shaped core 5, which is suitably secured to the handle as by screws 6 which pass through the core and into a pedestal 7, (Fig. 2). The electrical connections to the coil 4 consist of a pair of wires 8 one of which is connected to one coil, and the other to the other coil, these coils being connected together as usual to complete the circuit.

The core 5 projects from the coils 4 a sufficient distance to provide a proper magnetic field for the attraction of the armature 9 which is U shaped and is carried by a bar 10, the latter being provided with a foot 11 which is attached to and moves the moveable clipper blade 3, the rear end of the bar 10 being bent downwardly and carried by the spring 12 which is attached to the case 1.

Referring now to Figs. 3 and 4, the coils 4 are preferably mounted one above the other and the armature 13 is a straight bar vertically mounted and carried by the member 14 which is similar in its functions and mounted to the member 10 previously described and is provided with a foot 11 for attachment to the moveable blade 3.

Referring to Fig. 5 one of the coils 4 is mounted on the stationary pole piece 15 and the moveable pole piece 16 passes through a sufficiently large opening through the other coil 4 so that this pole piece may have the required amount of travel without striking the coil through which it passes. In this construction the pole piece 16 is pivotally connected as at 17 to the stationary pole piece 15 and its free end may be normally moved away from the free end of the pole piece 15 by a spring 18 which may be adjustable as by an abutment screw 19 which may pass through the clipper handle or be otherwise suitably mounted. The free end of the pole piece 16 carries the foot 11 for attachment to and operation of the moveable blade 3.

Referring now to Figs. 6 and 7, the armature 9 is attached to the moveable clipper blade 3, by means of foot 20 which carries the upstanding lugs 21 with which springs 22 cooperate the latter being adjustable by means of screws 23 to regulate the energy required to move the moveable blade. In this construction the moveable blade is guided as by rib 24 in a suitable recess in

the stationary blade 3 and is held in contact therewith by suitable means such as springs 25. The moveable blade and its moving mechanism as well as the stationary 5 blade and its carrying members may be pivotally connected to the casing or handle 1, the pivotal point being arranged as shown at 26 to the end that the clipper blades may be angularly moveable with relation to the 10 handle to accommodate various conditions of service, and the meeting portions of the handle and blade carrying members may be arcuately shaped as shown in Fig. 7, to accommodate this movement.

15. By arranging the coils longitudinally of the handle I am enabled to produce these coils in a size and arrangement which will permit of their being mounted in a handle sufficiently small to be comfortable in the 20 hand of the user and at the same time impart to the coils qualities which will permit of their continuous operation through comparative long periods of time without objectionable increase in temperature.

25. By mounting the armature so that its movement is toward and away from the axis of each coil, I eliminate the necessity for a bell crank or similar motion translating mechanism.

30. By mounting the armature as shown in all the figures except Fig. 5, the travel of the armature from and toward the pole pieces is uniform with relation to each pole piece so that the magnetic pull of each pole piece is 35 effective to move the movable clipper blade, where as if a bell crank were employed to move the clipper blade transversely of the handle while the armature moves longitudinally thereof a portion of the magnetic pull 40 would be lost by reason of the nearness of one end of the armature to the pivotal center.

If desired the spring 12 of Figs. 1 and 2 and its equivalent in Figs. 3 and 4 may be 45 mounted so that its tension may be varied as by a screw similar to the screw 19 of Fig. 5. Again the movable member 10 may be depended upon to hold the movable clipper blade into proper operating contact with the 50 stationary blade, or the springs 25 of Figs. 6 and 7 may be mounted on the construction of the other figures to hold the clipper blades in proper operating contact, and it is obvious that these springs may be made 55 adjustable or may be replaced by adjustable members which are not the nature of springs, these modifications being so obvious that it has not been deemed necessary to illustrate them.

60. Having thus fully described my invention, I claim:

1. In a clipper the combination of a handle portion, a stationary clipper blade carried thereby, a movable clipper blade cooperating with the stationary clipper blade,

an electro-magnetic coil mounted longitudinally in the handle portion, and an armature connected to the movable clipper blade to move the same, and means for mounting the armature to swing substantially transversely to the axis of the coil. 70

2. In a clipper the combination of a handle portion, a stationary clipper blade carried thereby, a movable clipper blade cooperating with the stationary clipper blade, an electro-magnetic coil mounted longitudinally in the handle and with its axis at an angle to the movement of the movable clipper blade, an armature for moving the movable clipper blade, means for mounting the armature to move substantially transversely to the axis of the coil, and a spring for moving the armature away from the axis of the electro-magnetic coil. 75

3. In a clipper the combination of a handle portion, a stationary clipper blade carried thereby, a movable clipper blade cooperating with the stationary clipper blade, a pair of electro-magnetic coils longitudinally mounted in the handle portion, an operating member for the movable blade, an armature carried by the operating member, and means for mounting the operating member to move substantially transversely to the axis of the coils. 80

4. In a clipper the combination of a handle portion, a stationary clipper blade carried thereby, a movable clipper blade cooperating with the stationary clipper blade, a pair of electro-magnetic coils longitudinally mounted in the handle portion, an operating member for the movable blade, an armature carried by the operating member, and means for mounting the armature to move substantially transversely to the axis of the coils said means providing substantially uniform movement of the armature to 100 each coil. 100

5. In a clipper the combination of a stationary clipper blade, a movable clipper blade cooperating therewith, an electro-magnetic coil mounted longitudinally in the handle and with its axis at an angle to the movement of the movable blade, a pole piece projecting from the coil, and an armature movably mounted at the side of the pole piece and for moving the movable clipper blade the movement of the armature being 110 115 toward the axis of the coil. 115

6. In a clipper the combination of a handle portion, a stationary blade carrying member pivotally connected to the handle portion, a movable clipper blade cooperating with the stationary blade, a coil mounted longitudinally in the handle portion, a pole piece projecting from the coil, an armature for moving the movable blade and adjacent one side of the pole piece, the pole piece and armature being positioned approximately in line with the pivotal connection between the 120 125 130

handle portion and the blade carrying member whereby the proper operating position of the armature will be maintained when the stationary blade carrying member is moved with relation to the handle portion.

7. In a clipper the combination of a handle portion, a stationary clipper blade carried thereby, a movable clipper blade co-operating with the stationary blade, an electro-magnetic coil mounted longitudinally in

the handle, a pole piece projecting from the coil at the end toward the clipper blades, an armature, and means for mounting the armature adjacent one side of the pole piece, a connection from the armature to move the movable clipper blade, and an adjustable spring for moving the armature away from the pole piece of the electro-magnet.

LEO J. WAHL.
